Patented May 4, 1926.

UNITED STATES PATENT OFFICE.

MAURICE JOSEPH STACK, OF COHOES, NEW YORK.

ROLL-UNWINDING STAND.

Application filed March 16, 1925. Serial No. 16,081.

To all whom it may concern:

Be it known that I, MAURICE J. STACK, a citizen of the United States, residing at Cohoes, in the county of Albany and State 5 of New York, have invented a new and Improved Roll-Unwinding Stand, of which the following is a specification.

The invention has for its object to provide a particularly simple roll unwinding stand 10 structure adapted for efficiently facilitating the unwinding of rolls of continuous length prepared cotton batting such as is used in upholstering automobiles or the like without damaging tensile strain or twist being exerted 15 on such batting during the unwinding thereof.

In my application for patent for method of preparing cotton batting for storage and shipment, Serial No. 16,078, filed March 16, 20 1925, I have disclosed a method as stated in which one of the features is the winding of the continuous lengths of batting into rolls. After these rolls have been shipped and are ready for use it is desired to unwind them 25 in a manner rendering that operation as simple and convenient as is possible and without danger of damaging twist or pull strain on the batting length. To efficiently accomplish the desired purpose stated I have 30 designed the unwinding stand disclosed herein, the novel structural features of which, and the manner of use thereof, will be readily apparent from the following detailed description, the appended claim and 35 the accompanying drawing, which:—

Figure 1 is a perspective view of the invention in use.

Figure 2 is an end view of the invention.

Figure 3 is a longitudinal section of the 40 roll supporting core.

Figure 4 is a detail cross section of the roll supporting core.

Figure 5 is an enlarged detail plan view 45 of one of the anti-friction bearings upon which the ends of the supporting core are mounted.

In the drawing 1 indicates the roll to be unwound and which is formed by winding the continuous length of batting 2 upon the 50 central hollow cylindrical core 3. In this form, the roll 1 wound upon the core 3, is shipped.

The stand includes the supporting framing 4, upon the upper cross bars 5 of each 55 end of which, and centrally of the width

thereof, are secured a pair of brackets 6 each of which serves as a convenient means for mounting a pair of closely positioned anti-friction bearing rollers 7 adapted to serve as anti-friction rest bearings for the 60 ends 8 of the core rod 9 which passes through the core 3 and is centrally spaced therein by the end plugs 10 for the purpose of providing the desired free rotating mounting of the roll 1 upon the stand so that the 65 batting length 2 may be paid-off as used without danger of twist or strain being exerted thereon.

End ferrules 11 may be provided on the ends of the rod 8—9 in position for engaging 70 the outer walls of the bearing brackets 6 to prevent longitudinal displacement of the said rod and each said bracket may be provided with an upwardly extended finger 12 75 extended in the direction in which the batting length is to be paid-off so as to prevent possibility of displacement of that rod in that direction, the shape of the finger being such as will just permit free movement of the rod ends 8 incident to the mounting 80 thereof into the crotch formed by the closely positioned rollers 7.

From the foregoing description, taken in connection with the accompanying drawing, it is thought the novel details of construction, manner of operation and advantages of my invention will readily apparent.

What I claim is:

A roll unwinding stand adapted to support a roll to be unwound comprising a supporting frame, a bracket supported at each end of said frame, anti-friction rollers carried by each bracket, a supporting core rod insertable through the center of a roll and adapted to have its end project therefrom to provide trunnions for having anti-friction bearing upon said anti-friction rollers, a pair of the said rollers being positioned closely adjacent each other in each bracket so as to provide a core rod receiving crotch 90 therebetween, the said rod having a ferrule at each end thereof adapted to engage said brackets for preventing longitudinal displacement of said rod, the said brackets each having an upwardly extended finger 95 projected in the direction in which the material is to be paid-off the roll and adapted to prevent displacement of the core rod in that direction.

MAURICE JOSEPH STACK.
